TREATMENT OF HYDROCARBON OILS

Jean Delattre Seguy, Chicago, Ill., assignor to
Universal Oil Products Company, Chicago, Ill.,
a corporation of Delaware

Application April 30, 1932, Serial No. 608,516

8 Claims. (Cl. 196—60)

This invention relates to the treatment of hydrocarbon oils and more particularly refers to an improved process and apparatus for the conversion of hydrocarbon oil accompanied by reduction of the residual conversion products to substantially devolatilized petroleum coke.

The present invention makes possible the production of high yields of motor fuel of maximum anti-knock value from the conversion of heavier hydrocarbon oils. Reduction of the residual conversion products to petroleum coke of low volatility permits the recovery of high yields of light liquid products while retreatment of a regulated portion of the light liquid product, in either vaporous or liquid state, under reforming conditions (conversion conditions which effect the improvement of light oils in anti-knock value without materially altering their boiling range) permits the recovery of a final light distillate product of high anti-knock value. In the present invention these two advantageous features are practiced in such a way that one augments the other, i. e. the highly heated distillate product of the system is utilized at a heat carrying medium to assist coking of the residual oil and devolatilization of the coke.

One specific embodiment of the present invention may comprise subjecting a hydrocarbon oil to conversion temperature at superatmospheric pressure in a heating coil and communicating reaction chamber, introducing the heated products into a reduced pressure coking zone wherein vaporous and residual liquid products separate and wherein residual liquid is reduced to petroleum coke of low volatility, subjecting vapors from the coking zone to fractionation, returning the heavy components of the vapors, which are condensed by fractionation, to the heating coil for further conversion, removing the lighter components of the vapors, remaining uncondensed by fractionation, from the fractionator, subjecting a portion thereof to condensation, collecting the resulting distillate and gas, subjecting the remainder of said uncondensed vapors to reheating in a separate heating coil under conditions of high temperature and super-atmospheric pressure, suitable to effect a substantial improvement in their anti-knock value, and introducing the highly heated vapors into the coking zone to commingle with the residual material therein and assist its coking and devolatilization.

It will be understood that many modifications of the specific embodiment above described may be employed without departing from the scope of the present invention. For example, the reac-

tion chamber may, when desired, be dispensed with and the heated hydrocarbon oil introduced from the heating coil directly into the reduced pressure coking zone. This type of operation is especially adaptable to the treatment of relatively heavy charging stocks such as residual oils, heavy crudes and the like, but may also be utilized in the treatment of lighter charging stocks by employing additional conversion time in the heating coil to compensate for the conversion time in the reaction chamber lost by its elimination. Another possible modification involves the use of a portion of the distillate from the receiver of the system as the material subjected to reforming and utilized as the heat carrying medium for the coking operation instead of the vaporous product from the fractionator, prior to its condensation. Use of the product in vaporous state may effect some saving in heating, comparable in quantity to the heat which would be extracted from this product by its condensation. Use of the cooled distillate, however, offers the advantage of being more easily handled than the heated vapors. These two operations are not entirely equivalent, however, as in one case the material subjected to retreatment contains a portion of the uncondensable gas produced by the system while in the other case substantially all of the gas has been separated from the distillate.

The attached diagrammatic drawing illustrates one specific form of apparatus embodying the features of the present invention and in which the process of the invention may be practiced. Raw oil charging stock for the system may be supplied through line 1 and valve 2 to pump 3 from which it may be fed through line 4, valve 5 and line 6 directly to heating coil 7 or it may pass, all or in part, from line 4 through line 8 and valve 9 to preheating coil 10 which is located within fractionator 11. The raw oil supplied to coil 10 is preheated by indirect contact with the heated vaporous conversion products in this zone and may pass from the coil in preheated state through line 12 and valve 13 into line 6 and thence to heating coil 7. It will be understood that other well known means of preheating the raw oil may be employed, although not shown in the drawing, and a portion or all of the raw oil may be introduced directly into fractionator 11, by well known means not illustrated, to commingle with the vapors, assist their fractionation and be returned from the fractionator, together with reflux condensate from this zone, by means of line 13', valve 14, pump 15, line 16, valve 17 and line 6, to heating coil 7.

Heating coil 7 is located within any suitable form of furnace 18 which supplies the heat required to bring the oil to the desired conversion temperature under the desired superatmospheric pressure. The heated oil is discharged from heating coil 7 through line 19 and may pass directly through line 20 and valve 21 into coking chamber 22, through line 23, and valve 24, or into coking chamber 22' through line 23' and valve 24'. However, the preferred method of operation, in most cases, is to pass the hot conversion products from heating coil 7 through reaction chamber 25, prior to their introduction into the coking zone, in which case the heated oil passes from line 19 through line 26 and valve 27 into reaction chamber 25 while both liquid and vaporous products are withdrawn from the lower portion of chamber 25 through line 28 and valve 29 into line 20 and thence to the coking zone, 10 as just described. Chamber 25, when utilized, is preferably maintained at substantial superatmospheric pressure which may be equalized with or somewhat reduced relative to that employed at the outlet from the heating coil. By means 15 of introducing the heated oil from heating coil 7 into the upper portion of the chamber 25 and withdrawing the products from the lower portion of the reaction chamber, the vaporous products, which gravitate to the bottom of the chamber 20 more slowly than the heavier liquid products, are subjected to a longer conversion time than the residual liquid in chamber 25. Any other well known method of operation may be employed in chamber 25 without departing from the scope of 25 the invention.

Chambers 22 and 22' are similar coking chambers preferably operated at substantially reduced pressure relative to that employed in the heating coil (and in the reaction chamber, when used). 30 It will be understood that one or any number of a plurality of such zones may be utilized for the coking operation; a plurality being preferred to provide additional space for the deposition of coke and permit prolonged operation of the process. When a plurality of coking chambers are employed they may be operated either alternately or simultaneously. Chambers 22 and 35 22' are provided respectively, with lines 30 and 30', controlled respectively by valves 31 and 31', which may serve as drain lines and also as means for the introduction of steam or water to hasten cooling of the chambers after their operation has been discontinued.

Vaporous products are removed from chamber 55 22 through line 32 and valve 33 and from chamber 22' through line 32' and valve 33'. The vaporous products of the system pass from the coking zone through line 34 to fractionation in fractionator 11. The heavy components of the 60 vapors are condensed within fractionator 11 to be supplied therefrom, as already described, to heating coil 7 for further conversion. Vaporous products remaining uncondensed in fractionator 11 are withdrawn from its upper portion through line 35 and a portion or all of this material passes through valve 36 to condensation and cooling in condenser 37. Condensed distillate and uncondensable gas passes from condenser 37 through line 38 and valve 39 to be collected in receiver 70 40. Uncondensable gas may be released from the receiver through line 41 and valve 42. Distillate may be withdrawn from the receiver to storage or to any desired further treatment through line 43 and valve 44. A portion of the 75 uncondensed vapors may be diverted from line

35 through line 45 and valve 46 to pump or compressor 47 and may be fed therefrom through line 48, valve 49 and line 50 to heating coil 51. In a similar manner a portion of the distillate from receiver 40 may, when desired, be withdrawn through line 52 and valve 53 to pump 54 from which it may be fed through line 55, valve 56 and line 58 to heating coil 51.

Heating coil 51 is located in a suitable furnace 57 of any desired form and the oil supplied thereto is heated to a relatively high temperature, preferably at substantial superatmospheric pressure, and is thence discharged through line 58 and may pass through line 59' and valve 68' into coking chamber 22' and/or through line 15 59 and valve 60 into coking chamber 22, commingling in the coking zone with the residual material therein and assisting its coking and devolatilization.

The heating coil wherein the raw oil charging 20 stock and reflux condensate are treated preferably utilizes a pressure ranging from 100 to 500 pounds, or thereabouts, per square inch with an outlet temperature ranging, for example, from 350 to 950° F. or thereabouts. Substantially this 25 same range of pressures is preferably employed in the reaction chamber. A reduced pressure ranging, for example, from 100 pounds per square inch down to substantially atmospheric pressure is employed in the coking zone and may be substantially equalized in the succeeding fractionating, condensing and collecting portions of the 30 system. A conversion temperature ranging, for example, from 900 to 1100° F. may be employed in the heating element wherein the distillate or 35 vaporous product is subjected to reforming, with a pressure in this zone ranging, for example, from 200 to 800 pounds, or thereabouts, per square inch.

As a specific example of the operation of the 40 process of the invention, a 30° A. P. I. gravity Mid-Continent topped crude is the charging stock for the system. The raw oil and reflux condensate are subjected to a conversion temperature of approximately 910° F. at a superatmospheric pressure of about 250 pounds per 45 square inch. A pressure of about 50 pounds per square inch is employed in the coking zone and vapors from the fractionator are reheated to a temperature of approximately 980° F., at a 50 superatmospheric pressure of about 400 pounds per square inch, and are then introduced into the coking zone. This operation may yield about 65% of motor fuel having an anti-knock value equivalent to an octane number of approximately 78 and in addition there may be recovered, per barrel of charging stock, about 65 pounds of petroleum coke having a volatile content of less than 5% and about 1000 cubic feet of 55 uncondensable gas.

I claim as my invention:

1. In a conversion process wherein hydrocarbon oil heavier than gasoline is subjected to cracking conditions of temperature and pressure in a heating coil and subsequently separated into vapors and unvaporized oil, and the unvaporized oil distilled to coke in a coking zone; the method which comprises fractionating said vapors in a fractionating zone to separate fractions heavier than gasoline from the gasoline boiling hydrocarbons, passing a portion of the gasoline boiling hydrocarbons in vapor form from the fractionating zone to a final condenser and condensing the same therein, collecting this 70 condensed portion of the gasoline boiling hydro- 75

carbons as a product of the process, passing the remaining portion of the gasoline boiling hydrocarbons from the fractionating zone to a second heating coil maintained at higher temperature than the first-named coil and heating the same therein sufficiently to enhance the anti-knock value thereof, and discharging the heated products from the second coil into contact with the unvaporized oil in the coking zone to assist the coking of the unvaporized oil therein.

2. In a conversion process wherein hydrocarbon oil heavier than gasoline is subjected to cracking conditions of temperature and pressure in a heating coil and subsequently separated into vapors and unvaporized oil, and the unvaporized oil distilled to coke in a coking zone; the method which comprises fractionating said vapors in a fractionating zone to separate the gasoline as vapor from the heavier insufficiently cracked fractions as condensate, removing the gasoline in vapor form from the fractionating zone and finally condensing and collecting a portion thereof as a product of the process, passing the remaining portion of the gasoline vapors, without prior condensation thereof, to a second heating coil maintained at higher temperature than the first-named coil and heating the same therein sufficiently to enhance the anti-knock value thereof, and discharging the heated products from the second coil into contact with the unvaporized oil in the coking zone to assist the coking of the unvaporized oil therein.

3. In a conversion process wherein hydrocarbon oil heavier than gasoline is subjected to cracking conditions of temperature and pressure in a heating coil and the heated oil subsequently flash distilled by pressure reduction in a reduced pressure zone; the method which comprises fractionating the vapors from the reduced pressure zone in a fractionating zone to separate fractions heavier than gasoline from the gasoline boiling hydrocarbons, passing a portion of the gasoline boiling hydrocarbons in vapor form from the fractionating zone to a final condenser and condensing the same therein, collecting this condensed portion of the gasoline boiling hydrocarbons as a product of the process, passing the remaining portion of the gasoline boiling hydrocarbons from the fractionating zone to a second heating coil maintained at higher temperature than the first-named coil and heating the same therein sufficiently to enhance the anti-knock value thereof, and discharging the heated products from the second coil into contact with the oil in the reduced pressure zone to assist the distillation thereof.

4. In a conversion process wherein hydrocarbon oil heavier than gasoline is subjected to cracking conditions of temperature and pressure in a heating coil and the heated oil subsequently flash distilled by pressure reduction in a reduced pressure zone; the method which comprises fractionating the vapors from the reduced pressure zone in a fractionating zone to separate the gasoline as vapor from the heavier insufficiently cracked fractions as condensate, removing the gasoline in vapor form from the fractionating zone and finally condensing and collecting a portion thereof as a product of the process, passing the remaining portion of the gasoline vapors, without prior condensation thereof, to a second heating coil maintained at higher temperature than the first-named coil and heating the same therein sufficiently to enhance the anti-knock value thereof, and discharging the heated prod-

ucts from the second coil into contact with the oil in the reduced pressure zone to assist the distillation thereof.

5. In a conversion process wherein hydrocarbon oil heavier than gasoline is subjected to cracking conditions of temperature and pressure in a cracking zone, unvaporized portions of the oil flash distilled by pressure reduction in a reduced pressure zone, and vaporous portions thereof fractionated in a fractionating zone to separate fractions heavier than gasoline from gasoline boiling hydrocarbons; the improvement which comprises passing a portion of the gasoline boiling hydrocarbons in vapor form from the fractionating zone to a final condenser and condensing and collecting the same as a product of the process, passing the remaining portion of the gasoline boiling hydrocarbons from the fractionating zone through a second cracking zone maintained at higher temperature than the first-named cracking zone and heating the same therein sufficiently to enhance the anti-knock value thereof, and discharging the heated products from said second zone into the reduced pressure zone to assist the distillation of the unvaporized oil therein.

6. In a conversion process wherein hydrocarbon oil heavier than gasoline is subjected to cracking conditions of temperature and pressure in a cracking zone, unvaporized portions of the oil flash distilled by pressure reduction in a reduced pressure zone, and vaporous portions thereof fractionated in a fractionating zone to separate fractions heavier than gasoline from gasoline boiling hydrocarbons; the improvement which comprises passing a portion of the gasoline boiling hydrocarbons in vapor form from the fractionating zone to a final condenser and condensing and collecting the same as a product of the process, passing the remaining portion of the gasoline boiling hydrocarbons from the fractionating zone through a second cracking zone maintained at higher temperature than the first-named cracking zone and heating the same therein sufficiently to enhance the anti-knock value thereof, and discharging the heated products from said second zone into the reduced pressure zone to assist the distillation of the unvaporized oil therein, the quantity of hydrocarbons passed from the fractionating zone to the second cracking zone being sufficient, after the heating thereof in said second zone, to distil the unvaporized oil to coke in the reduced pressure zone.

7. In a conversion process wherein hydrocarbon oil heavier than gasoline is subjected to cracking conditions of temperature and pressure in a heating coil and the heated oil subsequently flash distilled by pressure reduction in a reduced pressure zone; the method which comprises fractionating the vapors from the reduced pressure zone in a fractionating zone to separate fractions heavier than gasoline from the gasoline boiling hydrocarbons, passing a portion of the gasoline boiling hydrocarbons in vapor form from the fractionating zone to a final condenser and condensing the same therein, collecting this condensed portion of the gasoline boiling hydrocarbons as a product of the process, passing the remaining portion of the gasoline boiling hydrocarbons from the fractionating zone to a second heating coil maintained at higher temperature than the first-named coil and heating the same therein sufficiently to enhance the anti-knock value thereof, and discharging the heated prod-

ucts from the second coil into contact with the oil in the reduced pressure zone to assist the distillation thereof, the quantity of hydrocarbons passed from the fractionating zone to the second heating coil being sufficient, after the heating thereof in said second coil, to distil the oil in the reduced pressure zone to coke.

8. In a conversion process wherein hydrocarbon oil heavier than gasoline is subjected to cracking conditions of temperature and pressure in a heating coil and the heated oil subsequently flash distilled by pressure reduction in a reduced pressure zone; the method which comprises fractionating the vapors from the reduced pressure zone in a fractionating zone to separate the gasoline as vapor from the heavier insufficiently cracked fractions as condensate, removing the

gasoline in vapor form from the fractionating zone and finally condensing and collecting a portion thereof as a product of the process, passing the remaining portion of the gasoline vapors, without prior condensation thereof, to a second heating coil maintained at higher temperature than the first-named coil and heating the same therein sufficiently to enhance the anti-knock value thereof, and discharging the heated products from the second coil into contact with the oil in the reduced pressure zone to assist the distillation thereof, said remaining portion of the gasoline vapors being sufficient, after the heating thereof in said second coil, to distil the oil in the reduced pressure zone to coke.
